UNITED STATES PATENT OFFICE.

FRED QUINN, OF OLIVER, ILLINOIS.

VALVE-FACING DEVICE.

1,264,858.

Specification of Letters Patent. Patented Apr. 30, 1918.

Application filed October 25, 1917. Serial No. 198,497.

To all whom it may concern:

Be it known that I, FRED QUINN, a citizen of the United States, residing at Oliver, in the county of Edgar and State of Illinois, have invented certain new and useful Improvements in Valve-Facing Devices, of which the following is a specification.

My invention relates to a valve facing or truing device.

An important object of the invention is to provide a device of the above mentioned character, which is simple in construction, inexpensive to manufacture, and highly convenient in use.

Other objects and advantages of the invention will be apparent during the course of the following description.

In the accompanying drawings forming a part of this specification and in which like numerals are employed to designate like parts throughout the same,

Figure 1 is a side elevation of a device embodying my invention,

Fig. 2 is an end elevation of the same,

Fig. 3 is a transverse sectional view taken on line 3—3 of Fig. 1, and,

Fig. 4 is a detail section taken on line 4—4 of Fig. 1.

In the drawings, wherein for the purpose of illustration is shown a preferred embodiment of my invention, the numeral 10 designates the body portion of the device which serves as a jaw or element of a clamp. Preferably formed integral with the body portion or jaw 10 is a U-shaped member or bracket 11, having an upper horizontal head 12, provided with a screw-threaded opening 13, receiving a clamping screw or bolt 14. This clamping screw is provided with a head 15, carrying a transverse pin 16. The jaw 10 and screw 14 coact as elements of a clamp, for holding a sleeve 17, adapted to fit within an opening 18 in the jaw 10, which opening is V-shaped in cross-section, as shown.

Preferably formed integral with the body portion or jaw 10 is a U-shaped portion 19, comprising arms 20 and 21. The arms 20 and 21 are rigidly connected with a handle 22.

The forward end of the arm 21 is provided with a transverse screw-threaded opening 23, for the reception of a feed screw 24, having a head 25, carrying a pin 26.

The U-shaped portion or member 19 is provided near its connection with the han-

dle 22 with an enlarged portion 27, the upper surface of which is flat and is provided with a longitudinally extending groove 28, for the reception of a cutting element or grinder 29. This cutting element may be longitudinally adjusted within the groove 28 and clamped in adjustment at a desired position by a bolt 30, having screw-threaded engagement with the portion 27'. The cutter 29 is provided with a beveled cutting end or edge 31.

The numeral 32 designates a valve to be faced, having a beveled face 33. This valve is rigidly secured to a stem 34, inserted within and through the sleeve 17. It is obvious that the sleeve 17 may be longitudinally adjusted to be placed at a suitable distance from the valve, and that if the valve stem is not straight it will be detected upon being inserted within the sleeve. I contemplate using sleeves 17 of the same exterior diameter, but having openings or bores of different diameters for receiving valve stems of different diameters. By this means the valve stem will be retained in longitudinal alinement with the feed screw 24. It is obvious that by turning the feed screw 24 the valve 32 will be moved into proper engagement with the cutting edge 31 of the cutter.

In the operation of the apparatus, after the valve is arranged therein, as illustrated in Fig. 1, the entire apparatus may be horizontally or vertically disposed, and the free end of the stem or spindle 34 clamped within the jaws of a vise 35, whereby the valve is held stationary. The entire device may then be rotated by turning the handle 22.

If desired the stem 34 may be inserted in a lathe or drill chuck, the valve 32 rotated, while the handle 22 is held stationary.

If desired, a crank may be secured to the valve stem, and the valve turned by this means while the device is held stationary.

It is obvious that the invention is in no sense restricted to the particular manner in which it is operated, as the principle of operation is the same in each case.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. A facing tool, comprising a support having a longitudinal groove along one edge thereof; an alining sleeve adapted to be arranged in the groove and to receive the stem of a valve; an arm arranged over and above the groove; a clamp carried by the arm to secure the sleeve within the groove; 5 an adjustable cutting element carried by the support and adapted to contact with the face of the valve; a second arm arranged on the support; and a feed screw carried by the second named arm and having its longitudinal axis in alinement with the sleeve, and adapted to force the valve face into contact with the cutting element.
- 10 15 2. A facing tool comprising, a support; a

socket carried by the support and having one side open; a removable alining sleeve carried by the support and arranged within the socket; a clamping device connected with the socket and contacting with the sleeve; an arm connected with the support and arranged opposite and spaced from one end of the support; a feed screw carried by the arm and in longitudinal alinement with said sleeve; and a cutting element connected with the support and adapted to contact with the face of the valve. 20 25 30

In testimony whereof I affix my signature in the presence of two witnesses.

FRED QUINN.

Witnesses:

STEWART W. KINCAID,
PEARL CAMPBELL.
